Primary Examiner — Susan Moon Lee

(57)

I claim the ornamental design for a litter scooper, as shown and described.

DESCRIPTION

FIG. 1 is a first perspective view of the litter scooper, showing the handle oriented in a first position;
FIG. 2 is a front side view of the litter scooper;
FIG. 3 is a back side view of the litter scooper;
FIG. 4 is a left side view of the litter scooper;
FIG. 5 is a right side view of the litter scooper;
FIG. 6 is a top side view of the litter scooper;
FIG. 7 is a bottom side view of the litter scooper; and,
FIG. 8 is a second perspective view of the litter scooper, showing the handle oriented in a second position.
